(57) CLAIM

The ornamental design for a herb pot set, as shown and described.

DESCRIPTION

FIG. 1 is an identical front and rear view of a herb pot set showing my new design;

FIG. 2 is a top plan view thereof;

FIG. 3 is a bottom plan view thereof;

FIG. 4 is a right elevational view thereof;

FIG. 5 is a left side elevational view thereof;

FIG. 6 is a perspective view thereof;

FIG. 7 is a perspective view of a pot shown by itself without the other two pots or base for convenience of illustration;

FIG. 8 is a perspective view of the base shown without the three pots for convenience of illustration;

FIG. 9 is a perspective view of the herb pot set with the pots folded once; and,

FIG. 10 is a perspective view of the herb pot set with the pots folded twice.

The broken lines in FIG. 3 are included to show portions of the herb pot set that form no part of the claimed design.
